CLOTHES HANGER OR SIMILAR ARTICLE

Marc S. Landau, Dover, Del., assignor to International Latex Corporation, Dover, Del., a corporation of Delaware

Application August 13, 1956, Serial No. 42,594

Term of patent 14 years

(Cl. D80—8)

FIG. 1

Fig. 1 is a front elevational view of a clothes hanger or similar article embodying my design, of which the total surface of the clothes hanger is flat having a single continuous outline in the marginal edge thereof repoussé in form, and

Fig. 2 is a sectional view taken on the line 2—2 of Fig. 1.

I claim:

The ornamental design for a clothes hanger or similar article, as shown and described.
